UNITED STATES PATENT OFFICE.

JOSEPH ROEMER, OF PORTLAND, OREGON.

SPRING TRUCK-FRAME.

SPECIFICATION forming part of Letters Patent No. 228,781, dated June 15, 1880.

Application filed December 30, 1879.

To all whom it may concern:

Be it known that I, JOSEPH ROEMER, of Portland, in the county of Multnomah, in the State of Oregon, have invented an Improved 5 Spring Truck-Frame, of which the following is a specification.

My invention relates to the application of springs to a truck-bed in such a way that the springs do not take up much room under the 10 low truck-beds in common use, such trucks at present not having springs applied to them, so far as known, except in a common truck with high axles.

In Figure 1 of the drawings is shown a side 15 elevation of the truck, and in Fig. 2 a plan of same.

20 *a a* are springs; *b*, the goose-neck; *c*, a cross-beam, of wood or iron; *d*, the truck-bed; *e*, the hinder axle; and *f f*, the side beams, of wood or iron, called "reaches." These side reaches are bolted to axle *e* and the goose-neck *b*; or the goose-neck may be made in one piece, reaching the axle.

The cross-beam *c* is made use of for two purposes—one as a stretcher between the reaches, and the other as a support to the springs *a* at the fore part of the truck-bed *d*, the hinder pair of springs being bolted to the axle *e*.

25 In this arrangement of springs and frame a double purpose is gained, the first being the draft of the load by the frame or reaches *f*, attached solidly to the axles, they being so situated under the bed *d* that when the springs are overloaded the weight shall rest on the 30 frame or reaches *f*, and not endanger the springs

40 by breakage, the bed carrying the load being of such a size that it overlies the frame or reaches *f* at the sides sufficiently for holding the load when the springs are down in case of overloading.

45 The inventor is aware that springs have been applied to the hind axles of trucks in such a way that the wheels are drawn by the springs, the fore part of the bed or body having no springs; but in the device shown the fore and after parts of the load rest alike on the springs, and the wheels are drawn by the frame instead of the springs, and the springs, having the single duty of supporting the load, are much less liable to accidental breakage than in the first 50 case.

55 This form of truck-frame is believed to be new, embodying, as above, the principle of carrying the springs, and also the truck-bed, when overloaded.

50 There may be three or four of the reaches *f* attached to the goose-neck, and also two or more of the cross-beams *c*, in connection with the axle *e*, for holding more than two pairs of springs for heavy loads.

60 The springs may be of any of the forms usually used for such purposes.

I claim—

65 A truck-frame, as shown, consisting of the parts *a b c d e f*, in combination, substantially as described, and for the purpose set forth.

JOSEPH ROEMER.

In presence of—

F. W. LEWIS,

C. B. TALBOT.
